United States Patent Office.

LAWRENCE F. FRAZEE, OF JERSEY CITY, NEW JERSEY.

Letters Patent No. 79,111, dated June 28, 1868.

IMPROVEMENT IN LIFE-BOATS.

The Schedule referred to in these Letters Patent and making part of the same.

TO ALL WHOM IT MAY CONCERN:

Know ye that I, LAWRENCE F. FRAZEE, of Jersey City, and county of Hudson, and State of New Jersey, have invented certain new and useful Improvements in Life-Boats; and I do hereby declare the following to be a full, clear, and exact description of the same, reference being had to the annexed drawing, making part of this specification, in which—

Figures 1, 2, and 3 represent, respectively, the plan, side view, and midship cross-section of a boat which embodies my invention.

To enable others skilled in the arts to which my invention appertains to make and use the same, I will proceed to describe its nature, construction, and application.

The object of the life-boat is to save the lives of passengers by water after a great disaster has happened to the ship or steamboat carrying them. To accomplish this, it is of the highest importance that it may be made fully available when all on board the great ship is in confusion and derangement, and when both crew and passengers may be in such a state of excitement that all order and discipline are at an end, all attempts at method, and all exercise of skill and judgment, rendered impossible.

For this it is necessary that the boat shall be of such a character that it may be tossed overboard in any manner, however awkward, and into a sea however boisterous, without injury to itself or to the uprightness of its position. And it is further necessary that it shall be provided with stowage for bread and water, of such a character that these may be put in place before the ship leaves port, and be found intact and easily accessible when required after leaving the ship, notwithstanding the awkwardness and roughness with which it was launched into a stormy sea. It is also necessary that it may have its oars, compass, mast, and sail attached in such a manner that they will be certainly available when wanted. It is also essential that it shall be capable of passing through a heavy surf on a sand beach, and land its passengers in safety, even though it may have been managed by persons totally unskilled in such matters, and they laboring under great excitement.

It is because the so-called life-boats at present carried upon passenger-vessels do not comply with the foregoing conditions that I have essayed to invent improvements therein. The present life-boats can claim only that they will not sink when filled with water and with passengers, but they cannot claim that they will not be launched wrong side up, when this is done in a storm at sea or at any time, unless care and skill be employed, or that they will not capsize in very boisterous weather, and drown their passengers, or that they can pass with safety through a heavy surf.

The boat I have invented, and will now proceed to describe, will, however, fulfill all the conditions I have enumerated as essential, and if adopted will, in consequence, be a means of saving large numbers of shipwrecked persons who would otherwise perish.

My boat is made of sheet metal, and departs as widely from the ordinary forms as the little Monitor did from those of the war-vessels which preceded her advent. Instead of adhering to the modified form of the dug-out hollow log, as has heretofore been the practice, it more nearly represents the catamaran boats used to go through the surf at the Sandwich Islands and on the coast of Brazil.

It is formed by connecting two hollow semi-cylinders A A, made of sheet metal, and having a length equal to that of the boat, by a strong framework between them, in such a manner that they will be parallel with each other at a convenient distance apart, having the flat sides of the semi-cylinders facing inboard.

These metallic semi-cylinders are divided into a convenient number of water-tight compartments, into some of which may be stowed bread and water, access to which is obtained by means of openings, C D, on each side, so arranged as to close water-tight by well-known means in general use.

Near each end of the semi-cylinders there are a hollow sheet-metal bow and stern, B B, figs. 1 and 3. The dimensions of these are such that they give great buoyancy to the ends of the boat, at the same time that the form is favorable to its passage through the water.

When the boat is thrown overboard, it may right itself with either side up. This bow and stern are there-

fore so arranged that after the boat is in the water they may be drawn up with a small chain, and secured in the position shown in the drawing, favorable to the passage of the boat over the waves, through a surf, &c.

To accomplish this, a flattened tube is passed through the centre of motion, and secured to the heads water-tight, and through this is passed a strong iron rod, upon which the whole revolves, as required.

To the inboard ends of the bow and stern there is attached, by suitable hinges, a hollow sheet-metal bottom, E, in such a manner that when they are drawn up and secured, this is pressed down firmly against the cross-bars beneath it, forming a good bottom for the boat. The corresponding cross-bars above serve as thwarts for the rowers. The hinges referred to are shown at F F, fig. 2, in dotted lines.

The row-locks are shown at G G G, figs. 1 and 2. The mast is stepped at K, fig. 1, and there is a row-lock for a steering-oar fitted to the stern at L, figs. 1 and 2.

The compass is stowed in a covered cup let into one of the semi-cylinders near the stern, and shown at H. When required, it is expected that the person conducting the navigation of the boat will take it out and hold it in his hand, in which position the needle will assume its true magnetic position.

The longitudinal bars M M, &c., figs. 1, 2, and 3, are strong pieces of wood, firmly secured to the semi-cylinders, and serve as keels or rails, according to whichever side comes uppermost. To these are attached the life-lines N N, fig. 1.

The oars, with a mast and sail, are all lashed together when the boat is stowed on board ship, and then lashed to the boat, with the lashings carried all the way around, in such a manner that when the boat is thrown overboard, the fastenings are accessible whichever side comes uppermost, and even though the equipments may be on the under side, they can be loosened and drawn out from underneath without difficulty.

It will be observed that a boat of this construction will comply with all the conditions enumerated in this specification as essential to an efficient life-boat.

The provisions and water may be stowed in the compartments provided before the vessel leaves port, and after the boat has left the ship, and these are again brought to the mind by the hunger and thirst of the passengers, they are easily accessible whichever side of the boat is uppermost.

The boat will never capsize in a sea-way or in a surf, because so much of the displacement is at the sides and ends. The scientific naval architect will understand that this gives so great a stability that it will be impossible to capsize it, but a familiar illustration would be to secure two ordinary boats side by side, at a short distance apart, in such a manner that one of them could not be capsized without carrying the other bodily over it—an impossible feat for any sea or surf likely to be met with.

Each of the two semi-cylinders of my boat may be considered as the boat used in the above supposititious illustration.

The adjustable buoyant bow and stern, and the coupling of them with an adjustable bottom, are features which add greatly to the facility with which the boat can be navigated, and to the comfort of the passengers carried.

What I claim as my invention, and for which I desire to secure Letters Patent, is—

1. The combination of a buoyant and adjustable bow and stern, so arranged that whichever side of the boat floats uppermost, the desired form may be given to the ends thereof.

2. The adjustable bottom, so arranged that whichever side of the boat is uppermost it may be secured as low as possible, to give room to the feet and legs of the persons carried.

3. Connecting the adjustable bottom to the adjustable bow and stern in such a manner that when the latter are secured in the desired position, the former is also fixed as required.

4. The provision for stowing bread and water in such a manner that whichever side of the boat comes uppermost, it is all readily accessible to those on board, all for the purpose and in the manner substantially as described.

LAWRENCE F. FRAZEE.
